UNITED STATES PATENT OFFICE.

ALBERT J. GURNEY, OF CANTON, OHIO, ASSIGNOR TO THE AMERICAN MINE DOOR CO., OF CANTON, OHIO, A CORPORATION OF OHIO.

TROLLEY AND SIGNAL WIRE HANGER.

Application filed November 7, 1923. Serial No. 673,332.

To all whom it may concern:

Be it known that I, ALBERT J. GURNEY, citizen of the United States, residing at Canton, in the county of Stark and State 5 of Ohio, have invented certain new and useful Improvements in Trolley and Signal Wire Hangers, of which the following is a specification.

This invention relates to an improved 10 trolley and signal wire hanger for mines as employed in my improved signaling system for mines filed November 7, 1923, Ser. No. 673,329, and seeks, as one of its objects, to provide a hanger which, in addition to supporting a trolley wire, will also sustain a conductor wire over the trolley wire in close spaced relation thereto.

The invention seeks, as a further object, 15 to provide a hanger wherein the wires may be readily attached thereto to be firmly held by the hanger.

And the invention seeks, as a still further object, to provide a hanger embodying 20 clamping means common to both wires for binding the jaws of the hanger in engagement therewith.

Other and incidental objects will appear hereinafter.

In the drawings:

30 Figure 1 is a side elevation of my improved hanger, parts being broken away and shown in section, and

Figure 2 is a sectional view particularly 35 showing the structure of the clamping jaws of the hanger.

In carrying the invention into effect, I 40 employ an insulator 10 which may be of any approved construction but will include a depending stud 11 and may be suitably secured directly to the roof of a mine or other supporting means such, for instance, as a cross beam 11' in the mine. Detachably connected to the stud are companion 45 elongated clamping jaws 12 and 13 grooved at their lower margins to receive a trolley wire therebetween, as conventionally illustrated at 14. Centrally thereof, the jaws are channelled at their inner sides to define mating portions of a longitudinal bore between the jaws and fitting in said bore is a sleeve 15 of suitable insulating material, the sleeve accommodating a conductor wire 16. Formed on the ends of the jaws to 50 snugly surround the ends of said sleeve are

the mating halves of conical nipples 17 and 55 threaded over said nipples are nuts 18 which, as will be perceived, may be adjusted for clamping the jaws in engagement with the sleeve 15. Rising from the jaw 12 medially thereof is a cylindrical shank 19 60 overhanging the jaw at its inner side and cut away at its upper end along the outer side of said shank to define a terminal boss 20. As shown in Figure 2, the jaw 13 is formed medially with a transverse channel 65 21 and rising from the jaw to produce a continuation of said channel is a semi-cylindrical sleeve 22 extending about the shank and provided at its upper end with a ring 23 fitting over the boss 20, the channel 21 70 permitting the jaws 12 and 13 to be assembled. Thus, the ring 23 will normally maintain the jaws in assembled relation, and formed in the shank 19 is an axial socket 75 accommodating the stud 11. Accordingly, the jaws may be readily attached to the insulator when, after the wires 14 and 16 have been arranged in place, the nuts 18 may be applied for tightening the jaws. As will be noted, the hanger is constructed to support the wire 16 above the trolley wire 80 in close spaced relation thereto, and in my improved signaling system previously identified, suitable annunciations are electrically connected with the wire 16 so that when the trolley wire is pressed upwardly by the passage of a mine car trolley along the trolley wire, a circuit will be closed through the wire 16 for energizing the annunciations.

Having thus described the invention, what 90 is claimed as new is:

1. A hanger of the character described including coacting jaws to engage a wire, and independently adjustable means rotatably mounted on the opposite ends of the 95 jaws and positively engaging said ends for securing the jaws together.

2. A hanger of the character described including coacting jaws to engage a wire and formed to receive a second wire therebetween, means accommodated between the jaws insulating the latter wire from said first mentioned wire, and means for drawing the jaws toward each other.

3. A hanger of the character described including coacting jaws to engage a wire and channelled to receive an insulator therebetween accommodating a second wire, and

- means for drawing the jaws toward each other about said insulator gripping said first mentioned wire.
4. A hanger of the character described including coacting jaws to engage a wire and provided at their ends with threaded nipples, and nuts screwed upon said nipples clamping the jaws in engagement with the wire.
10. 5. A hanger of the character described including companion jaws provided at their ends with nipple portions mating to define nipples at the extremities of the jaws, and nuts screwed upon said nipples and adjustable for clamping the jaws in engagement with a wire.
6. A hanger of the character described including coacting jaws channeled to receive an insulator therebetween accommodating a wire and provided at their ends with nipple portions mating to define nipples surrounding the ends of the insulator, and nuts adjustable upon said nipples for clamping the jaws about the insulator.
25. 7. A hanger of the character described including coacting jaws channeled to define a bore therebetween and provided at their ends with nipples, an insulator fitting in said bore and adapted to accommodate a wire therethrough, and nuts adjustable upon said nipples for clamping the jaws about the insulator.
30. 8. A hanger including companion jaws to coact with a wire, one of the jaws being formed with an overhanging shank terminating in a boss and the other of the jaws being formed with a sleeve to accommodate said shank and provided with a ring to fit over said boss connecting the jaws with each other, and means for drawing the jaws together.
35. 9. A hanger of the character described including coacting jaws to engage a wire, and rotatable means independently adjustable longitudinally of the jaws for drawing the jaws toward each other.
10. A hanger of the character described including coacting jaws to engage a wire and formed to accommodate a second wire therebetween, and means adjustable longitudinally of the jaws for drawing the jaws toward each other. 50
11. A hanger of the character described including coacting jaws to engage a wire, and rotatable means straddling the ends of the jaws and independently adjustable for drawing the jaws toward each other. 55
12. A hanger of the character described including coacting jaws to engage a wire and formed to receive a second wire therebetween, and means straddling the jaws securing the jaws together. 60
13. A hanger of the character described including coacting jaws to engage a wire and provided at their ends with threaded terminals, and rotatable means screwed upon said terminals securing the jaws together. 65
14. A hanger of the character described including coacting jaws to engage a wire and formed to receive a second wire therebetween, the jaws being provided at their ends with projections, and means straddling said projections securing the jaws together. 70
15. A hanger of the character described including coacting jaws to engage a wire, one of the jaws being formed with a shank provided at its upper end with a terminal boss and the other of the jaws being formed with a ring to surround said boss resting upon the upper end of said shank for sustaining the latter jaw against downward movement relative to the former jaw, and means securing the jaws together. 75
16. A hanger of the character described including coacting jaws provided at their ends with nipple portions mating to define nipples at the extremities of the jaws, and independently adjustable means fitting over said nipples securing the jaws together. 80
- 85
- In testimony whereof I affix my signature.

ALBERT J. GURNEY. [L. S.]
